INVENTOR

BY Victor J. Evans

ATTORNEY

WITNESS:

UNITED STATES PATENT OFFICE.

DODLEY H. POWELL, OF NORRIS, MONTANA.

POWER-DRIVEN HACK SAW.

Application filed March 21, 1924. Serial No. 700,908.

To all whom it may concern:

Be it known that I, DODLEY H. POWELL, a citizen of the United States, residing at Norris, in the county of Madison and State 5 of Montana, have invented new and useful Improvements in Power-Driven Hack Saws, of which the following is a specification.

This invention relates to saws and has for its object the provision of a novel hack saw 10 provided with electric motor means for imparting reciprocatory movement to the blade, the device being capable of manual movement at the same time so as to effect rapid cutting with very little effort on the 15 part of the user.

An important and more specific object is the provision of a device of this character equipped with spring means normally drawing the blade in one direction this means 20 assisting movement of the blade and being, moreover, adjustable so that the tension may be varied.

An additional object is the provision of a device of this character which will be 25 simple and inexpensive in manufacture, easy to use, positive in action, efficient and durable in service and a general improvement in the art.

With the above and other objects and ad- 30 vantages in view the invention consists in the details of construction to be hereinafter more fully described and claimed and illus- trated in the accompanying drawings, in which:

Figure 1 is a side elevation of the device, 35 Figure 2 is an edge view with parts in section.

Referring more particularly to the drawings I have shown the device as comprising 40 a frame 10 which is of the same general shape provided for ordinary hack saws and which is formed at one end with an extension 11 defining a handle 12. The main portion of the frame includes front and rear 45 arms 13 and 14 and the handle portion includes an element 15 secured to the arm 14. For convenience in handling, I may also provide a handle 16 secured upon the center 50 of the main frame so as to facilitate guiding or lifting the device.

Secured upon the extension 11 is an elec- 55 tric motor 17 of some suitable construction

having its shaft 18 carrying a disk 19 equipped with a wrist pin 20. This consti- 55 tutes the driving mechanism.

Carried by the frame 10 at a point spaced from the arm 13 is a support 21 through which is slidable a bar 22 having the usual pin 23 upon which the hole at one end of a hack saw blade 24 may be engaged. Slid- 60 able through the arm 14 is a similar bar 25 carrying a pin 26 on which the other end of the blade is engaged, the purpose of this particular arrangement being to permit 65 changing blades when necessary.

Pivotedly connected with the wrist pin 20 is a pitman or link 27 which is pivotedly connected with the rear end of the bar 25 so that when the motor is operated the bar 70 25 and consequently the hack saw blade will be reciprocated.

An important feature is the provision of a tension spring 28 which is connected with the bar 22 and with an adjusting screw 29 75 threaded through the arm 13.

In the operation it will be apparent that when the motor is in action, the blade 24 will be reciprocated rapidly with a very short stroke. When sawing, it is intended 80 that the operator move the entire device slowly so that all portions of the blade will be caused to act upon the material being cut. The reason for this is to avoid overheating 85 the blade and to make the wear thereon uniform. As a matter of fact the manual effort involved is very slight so that very rapid and efficient work may be done with the utmost ease.

While I have shown and described the 90 preferred embodiment of my invention it is of course to be understood that I reserve the right to make such changes in the form, construction and arrangement of parts as will not depart from the spirit of the inven- 95 tion or the scope of the subjoined claims.

Having thus described my invention I claim:

1. A device of the character described comprising a frame including spaced arms 100 and having an extension terminating in a handle, a motor mounted on the extension and having its shaft carrying a disk equip- 105 ped with a wrist pin, bars slidable through the frame and formed for detachable con-

nection of a saw blade therebetween, and a pitman connected with one bar and with said wrist pin.

2. A device of the character described comprising a frame including spaced arms and having an extension terminating in a handle, a motor mounted on the extension and having its shaft carrying a disk equip-

ped with a wrist pin, bars slidable through the frame and formed for detachable connection of a saw blade therebetween, and a pitman connected with one bar and with said wrist pin, and adjustable spring means opposing movement of the blade in one direction.

DODLEY H. POWELL.
